UNITED STATES PATENT OFFICE.

WALTER W. SIBSON, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

HOSIERY-DRYING MACHINE.

Application filed May 13, 1924. Serial No. 712,965.

This invention relates to a hosiery drying machine embodying mechanism for traversing a series of forms through a drying zone, with provision for oscillatory expulsion and 5 return to effect removal of dried articles and their replacement by fresh wet ones.

An object of my invention is to provide novel means for expelling and returning successive forms by radial rocking action, relative to the drying zone, as they are progressed past an attendant's station whereby "stripping" and "boarding" are conveniently accomplished with precision and rapidity.

Another object is the provision of novel 15 mechanism whereby the series of forms are intermittently progressed with synchronized expulsion and return of relatively separated units.

Other objects and attendant advantages 20 will—later on—be referred to, or become obvious from the following detailed description of one practical embodiment of my invention; but it is to be understood that the same is by way of example only, while the 25 features of novelty are succinctly defined in the subjoined claims.

In the further disclosure of this invention reference is made to the accompanying drawings, constituting a part of this specification; 30 and in which like characters designate the same or corresponding parts in all the views.

Fig. I, is a vertical section of a hosiery drying machine conventionally embodying this invention.

Fig. II, is a plan view of the same with parts broken away, and in section, to better disclose certain underlying structural features.

Fig. III, is a broken vertical section of a 40 modified form of the invention.

Fig. IV, is a fragmentary transverse section of the preceding figure.

Fig. V, is a detail view illustrating the manner in which the hosiery forms are supported by superposed rotary conveyors.

Fig. VI, is a detail view of the mechanism operative to rock successive forms out of, and into, the drying zone at the attendant's station.

Fig. VII, is a fragmentary detail view 50 illustrative of the manner in which certain instrumentalities co-operate to enter a clothed form into the drying zone; and,

Fig. VIII, is a similar view exemplifying the reverse operation. 55

Referring more particularly to Figs. I and II, it will be seen that the drying machine comprises a cylindrical chamber comprehensively designated by the numeral 9, with a lateral offset portion 10 providing a location 60 whereat an attendant or attendants, is, or are, stationed to effect "stripping" and "boarding" of successively expelled hosiery forms 11, before their return into the machine, as hereafter fully explained. This 65 chamber 9 is divided intermediate its top 12 and bottom 13 by a rotatable diaphragm 14 having a series of radial slots 15 in which the aforesaid forms 11 are engaged during progression through the drying zone 16; 70 and, said diaphragm divides the chamber 9 into upper and lower compartments *a*, *b*, respectively, the former *a* including the drying zone 16, whereas the latter *b* houses certain mechanism, hereafter described, and protects 75 the same from injurious action by surrounding moist atmosphere, as well as safe-guarding the operative or operatives adjacent thereto.

Mounted concentrically over the compartment *a* by means of transverse supports 17, is a hood 18, having an outlet 19 under control of a damper 20 in the well known way. Co-axial within the chamber 9, and supported by oblique angle-struts 21, is a cylindrical 85 conduit 22 having its upper end partially closed-in to provide an opening 23, in which is located a horizontally rotatable fan 24, the shaft whereof is journaled in a bearing 25 supported by opposingly directed channel 90 members 26. Rotary motion is imparted to the fan 24 by a miter-couple 27 driven by a radially disposed shaft 28, journaled in bearings 29; and said shaft 28, in turn, has motion imparted thereto from any convenient 95 source of power transmitted to the pulley couple 30.

Arranged within the cylindric chamber 9, are upper and lower headers 31, 32 respectively, connected by vertical pipes 33 through 100 which the heating medium is circulated in the well known way; and, as will be best appreciated from Fig. I, when the fan 24 is rotated, a constant circulation of heated air through the drying zone 16 will be maintained with a more or less looped direction 105.

flow, as indicated by the arrows on said figure. Obviously, atmospheric air will be constantly drawn into the open top 12 of the compartment *a* and mix with the moist-air drawn off from the wet hosiery and circulated in the manner above referred to; but it will be equally clear that by regulating the damper 20, all air may be drawn from the radiating surfaces of the pipes 33, and headers 31, 32, over the hosiery clothed forms 11, and exhausted through the outlet 19. On the other hand a portion only of the heated moist-air may be re-circulated by partially closing the damper 20, with the balance thereof exhausted by way of the outlet 19.

In some instances, and where it is desirable that all the moisture-laden air drawn off from the clothed forms 11 shall be completely exhausted—from the drying zone 16,—I conveniently adopt the upper compartment assembly shown by Fig. III, and from which it will be observed that the compartment *a* is closed in by a cover 34 snugly surrounding, but not extending below, the upper header 31. Similarly the shell or skin of the lower compartment *b* embraces, but terminates co-planal with the upper surface of, the lower headers 32, whereby the nest of vertical tubes 33 constitutes an outer surrounding apertured-wall for the drying zone 16. In this form of the invention, I make the cylindrical conduit 22' of perforate material below the planal level of the fan 24, and connect it co-extensive with the hood 18; all of which will be readily understood by anyone conversant with the art to which said invention appertains. In so far as the associated parts are concerned, it will be noted that they are the complements of those previously described in connection with Figs. I and II, hence they are correspondingly designated, while further description is deemed unnecessary. Furthermore the changed directional flow of the drying medium is indicated by the arrows on Fig. III.

The rotatable diaphragm 14, as best seen by Fig. I, is secured in any convenient manner to the upper end of a vertical shaft 35 journaled in bearings 36 mounted within the lower compartment *b*. This shaft 35 also affords rigid support for a pair of superposed spiders 37, 38, and said shaft is adapted for comparatively slow intermittent rotation by means of a crown gear 39 meshing at intervals with the constantly rotating dwell-spaced gear 40 on the inner end of a counter-shaft 41, journaled in bearings 42. This counter-shaft 41 is rotated by means of a worm drive 43, and vertical shaft 44, in turn driven by a miter couple 45 from the hereinbefore referred to radial shaft 28.

Referring again to the hosiery forms 11, each of which is adapted for radial rocking

zone 16, it will be observed that they are supported by carrier shoes 46 of appropriate type to clampingly receive individual forms of different size and pattern. Each carrier shoe 46 and associated parts being in counterpart I will, for the sake of brevity, confine the following description to a single unit. Integral with the carrier shoe 46 are spaced lugs 47, 48 to the former of which is removably pinned one arm of a triple-jointed or pivoted linkage, comprehensively designated by the letter *l* and, embracing two main members 49, 50. The member 49, it will be observed is of angled configuration to afford a relatively short arm 51, an intermediate arm 52, and a comparatively longer arm 53; whereas the other member 50 is of obtuse-angled formation to provide a rocker 54 and a short tappet section or trip 55, whereby the linkage *l* is influenced to rock the connected form 11, as hereafter fully explained. The intermediate arm 52 aforesaid is conveniently connected, by a short link 56, to the lug 48, whereby provision is made to accommodate different forms and sizes of carrier shoes 46, while the obtuse angled member 50 is pivoted at 57 to intermediate radial lugs 58 at the circumferential edge of the lower spider 38. It is here noticeable that the rocker portion 54 of the link member 50 is afforded radial guidance in an elongated slot 59 of the upper spider 37; said slot having a co-aligned stepped recession 60 for complementary accommodation of the elbow portion of the link member 49, as will be readily appreciated by an examination of Figs. I and II, more particularly.

Outward throw of the triple-pivoted linkage *l* just described, is controlled by a lateral pin or stud 61 at the free end of the arm 53 cooperating with a stop lug 62 integral with, and on the underside of, the spider 37, whereas inward movement is limited by the edge of the rocker 54 being brought into abutment with the inclined inner end 63 of the elongated slot 59, and lateral repose of the intermediate arm 52 upon the aligning upper surface edge of said slot. It is also to be noted that the rocker 54 is provided with a lateral pin or stud 64, the function of which will be later on fully set forth.

The means operative to effect actuation of successive linkages *l*, whereby the associated form 11 is radially rocked and expelled from the drying zone 16 for stripping and re-clothing, and thereafter similarly returned into said zone comprises opposingly rotated cams 65, 66. These cams 65, 66 are the complement of one another, and are of the intermittent semi-cylindric variety, being rigidly attached to, or formed integral with, co-aligned stub shafts 67, 68 journaled in bearings 69, 69; and each of said stub shafts is fitted with a bevel gear 70, for differential drive by a common or intermediate gear 71

on a transverse radial shaft 72, journaled in bearings 73, and continuously rotated by a bevel gear 74 in mesh with a crown gear 75 on the vertical shaft 35, hereinbefore referred to. As will be best seen by Fig. II, the cams 65, 66 are in somewhat spaced relation for a purpose later on explained, but it will be obvious that they may be otherwise located relative to one another.

10 To afford exit and entry for the forms 11 relative to the drying zone 16, the upper chamber or compartment "a" is provided with vertical openings 76, 77, respectively, and said openings have associated baffles 15 78, 79, the former 78, of which is constituted by a radially stepped wall, intermediate the shed of the cylindrical chamber 9 and concentric conduit 22; whereas the latter, 79, is of angular cross-section and functional to 20 guide consecutive forms with proper registration into the aforesaid openings, as well as to shield the adjacent ends of the headers 31, 32, and vertical pipes 33, from localized cooling due to their close juxtaposition to 25 the openings 76, 77.

The operation of my novel type of hosiery drying machine is as follows:

Motion being imparted to the radial shaft 28 it will be clearly apparent from the preceding description that the fan 24 and countershaft 41 will be continuously rotated, while said shaft 41 will, in turn, intermittently rotate the spiders 37, 38, and associated diaphragm 14 through the medium of 35 the dwell-spaced and crown gears 40, 39, respectively.

Simultaneous with each part rotative movement of the vertical shaft 35, spiders 37, 38, and diaphragm 14, motion is imparted to the transverse shaft 72 with consequential rotation in opposed directions of the stub shafts 67, 68 and semi-cylindrical cams 65, 66. Referring more particularly to Figs. II, VII and VIII, and assuming that 45 the cams 65, 66, are—as indicated by the associated arrows—respectively rotated in clockwise and counter-clockwise directions, it will be seen that the advancing rise 40—Fig. VIII—of the cam 65, will engage the 50 tappet 55 of the linkage member 50 and swing the same radially inwards relative to the vertical center line of the machine. As a result of the motion just described the linkage 7 will function and expel or rock 55 the form 11 carried thereby from the shaded position shown at the left-hand side of Fig. I, to the juxtaposed position indicated in flat outline; or exterior to the drying zone 16, over the offset portion 10. Incident to 60 the rocking of the linkage member 50, it will be observed that, the associated three-armed member 49 has received a differential motion whereby the long arm 53 has moved upwardly into abutment below the 65 spider 37 with the stud 61 thereon limiting

its outward throw by engagement with the stop lug 62. At this juncture, it is well to note that the pin or stud 64 serves as the third pivotal point of the linkage 7, over which the arm 53 pivotally slides to effect 70 rocking of the form 11, from an inwardly inclined drying zone progressing position to exterior vertical disposition for stripping and reclothing, as will be clearly understood on examination of the left-hand side of 75 Fig. I.

Now it will be readily apparent that the cam 66 by its advancing rise 81 will simultaneously have functioned in a reverse manner, whereby the linkage 7 acted upon has 80 operated to rock the form 11 carried thereby from exterior exposure back into the drying zone 16. At this point I desire again to draw particular attention to the spaced relation of the cams 65, 66 which makes provision 85 for actuation of separated linkages 7, whereby the exposed forms 11 are progressed exteriorly of the machine a sufficient period of time to accommodate stripping, reclothing and inspection successively with ease 90 and facility, but it will be clear that such relative spacing of said cams may be otherwise than as shown without interfering with their proper functioning.

From the preceding explanatory description 95 it will be obvious that immediately a form 11 is expelled from the drying zone 16 over the offset portion 10, an attendant stationed at "S"—for example—can strip the dried article therefrom. Subsequent intermittent movements of the spiders 37, 38 will 100 progress the stripped form 11 to reclothing location "B"—for instance—whereat another operative will place a fresh wet article thereon, when the next succeeding part rotative movement of said spiders will advance the 105 form to position "C" ready for return into the drying zone 16, as before set forth. Obviously the offset portion 10 is made open-topped, as indicated at 82, to accommodate 110 unimpeded progression of the forms 11 and associated linkages 7 from the position designated "S" to that characterized "C".

While I have described the spiders 37, 38 and linkages 7 as intermittently operated, it 115 will be readily understood that, by appropriate gearing-down, said spiders may be continuously rotated with a comparatively slow motion, whereas the cams 65, 66 would be correspondingly geared-up to oscillate 120 the linkages 7 with a quick and positive action at the points of form expulsion from, and return to, the drying zone 16. Furthermore the lower compartment "b" of the machine may be surrounded by reticulate material instead of being closed-in as hereinbefore set forth.

From the foregoing description and a 125 study of the drawings it will be quite clear to anyone in the least conversant with the

art to which this invention appertains, that I have devised a simple and very efficient automatic machine for drying hosiery and other articles, the inherent advantages and 5 general utility whereof are so obvious, that further elaboration is deemed unnecessary. Still further it is to be noted that while I have described and explained one practical embodiment of my invention, the same is 10 susceptible of varied modification without departing from the true intent and scope thereof, as tersely defined by the subjoined claims.

Having thus described my invention, I 15 claim:

1. In a drying machine having a zone open to the atmosphere, superposed spiders conveying forms therethrough in relative stationary disposition, and means functional 20 to radially rock successive forms outwards and inwards with respect to the drying zone for stripping and reclothing.

2. In a drying machine having an annular zone open to the atmosphere, superposed 25 spiders conveying forms therethrough in relative stationary disposition, and cooperative means functional to radially expel and return successive forms with respect to the annular zone for stripping and reclothing.

3. In a drying machine having an annular zone open to the atmosphere, means conveying 30 a series of form carriers therethrough in radial disposition, said means including spaced rotatable spiders, and a triple-jointed linkage supporting each said carrier with capacity for outward and inward oscillation.

4. In a drying machine having an annular zone open to the atmosphere, means conveying 35 a series of form carriers therethrough in radial disposition, said means including concentrically superposed spiders, and a triple-jointed linkage supporting each said form carrier with capacity for radial oscillation.

5. In a drying machine having an annular zone open to the atmosphere, means conveying 40 a series of form carriers therethrough in radial disposition, said means including concentrically superposed spiders, a triple-jointed linkage supporting each said carrier with capacity for radial oscillation, and an associated diaphragm having radial slots to receive the forms whereby they are held relatively stationary during progression through 45 the drying zone.

6. In a drying machine having an annular zone open to the atmosphere, means conveying 50 a series of form carriers therethrough in radial disposition, said means including concentrically superposed spiders, a triple-jointed linkage supporting each said form carrier with capacity for radial oscillation, an associated diaphragm having radial slots to receive the forms whereby they are held relatively 55 stationary during progression through

the drying zone, and means for intermittently progressing said spiders and diaphragm simultaneously with actuation of the linkage aforesaid.

7. In a drying machine having an annular zone open to the atmosphere, means conveying 60 a series of form carriers therethrough, said means comprising upper and lower concentrically rotatable spiders, and a triple-jointed linkage supporting each said carrier, the lower spider serving as a fulcrum for the triple-jointed linkage and the upper one as a guide support therefor.

8. In a drying machine having an annular zone open to the atmosphere, means conveying 65 a series of form carriers therethrough, said means comprising upper and lower concentrically rotatable spiders, a triple-jointed linkage supporting each said carrier, the lower spider serving as a fulcrum for the triple-jointed linkage and the upper one as a guide support therefor, in combination with a superposed diaphragm functional to prevent lateral displacement of the forms 75 during progression through the annular zone aforesaid.

9. In a drying machine including a series 80 of rockable form carriers, the combination of a spider functional as a guiding support for the form carriers, said spider having a series of radial slots each with an inclined inner end and a co-aligned outer recession for the purposes specified.

10. In a drying machine having an annular zone open to the atmosphere and means 85 progressing form carriers therethrough with predetermined directional disposition, individual means functional to radially rock each successive form outwards and inwards with respect to the drying zone comprising 90 a triple-pivoted linkage including a rocker and three-armed cooperative members, the latter having two of its arms attached to the form carrier and the third operative as an outward-throw limiting means.

11. In a drying machine having an annular zone open to the atmosphere and superposed spiders progressing form carriers therethrough with predetermined directional disposition, individual means functional to 95 radially rock each successive form outwards and inwards with respect to the drying zone comprising an angled rocker pivoted on one spider to afford a tappet, and a graduated three-armed cooperative member, the shorter arms of which are detachably connected to the form carrier, and a stud on the longer arm for engagement with a stop lug on the other spider for the purpose specified.

12. In a drying machine having an annular zone open to the atmosphere and superposed spiders progressing form carriers therethrough with predetermined directional disposition, an obtuse angled rocker for each 100 form carrier pivoted to the lower spider to 105

afford a depending tappet, a graduated three-armed cooperative member the shorter arms of which are detachably connected to said form carrier, a stud on the longer arm for engagement with a stop lug on the upper spider, and a fulcrum on the angled rocker over which the longer arm aforesaid rides to change the longitudinal inclination of the form when radially oscillated relative to the 10 annular zone for stripping and reclothing.

13. In a drying machine having an annular zone open to the atmosphere and superposed spiders progressing form carriers therethrough with predetermined directional disposition, an obtuse angled rocker for each form carrier pivoted to the lower spider to afford a depending tappet, a graduated three-armed cooperative member the shorter arms of which are detachably connected to said form carrier, a stud on the longer arm for engagement with a stop lug on the upper spider, a fulcrum on the angled rocker over which the longer arm aforesaid rides to change the longitudinal inclination of the form then radially oscillated, and means comprising aligned reversely rotatable cams operative to effect the radial oscillation aforesaid.

14. In a drying machine having an annular zone open to the atmosphere and superposed spiders progressing form carriers therethrough with predetermined directional disposition, individual means functional to radially rock each successive form 35 outwards and inwards with respect to the annular zone comprising an obtuse angled rocker pivoted to the lower spider to afford a depending tappet, a graduated three-armed cooperative member the shorter arms 40 whereof are detachably connected to the

form carrier, a stud on the longer arm for engagement with a throw limiting stop lug on the upper spider, a fulcrum on the angled rocker over which the longer arm aforesaid rides to change the longitudinal inclination 45 of the form, and aligned reversely rotatable semi-cylindrical cams for co-action with the tappet to effect the radial rocking aforesaid.

15. In a drying machine including an annular drying zone open to the atmosphere, superposed spiders conveying form carriers therethrough in relative radial disposition, means functional to rockingly expel and return successive forms with respect to said drying zone, and means effective to intermittently progress the form carriers with synchronous actuation of the rocking means.

16. In a drying machine including an annular drying zone open to the atmosphere, superposed spiders conveying form carriers therethrough with radial disposition, means functional to rockingly expel and return relatively separated carriers with respect to said drying zone, and means effective to intermittently progress the form carriers with synchronous actuation of the rocking means of relatively separated radial units.

17. In a drying machine embodying a conduit with a concentric cylindrical heating means affording an intervening annular drying zone, the combination of means functional to divert into said drying zone—for re-circulation—a controllable quantity of the moisture-laden air passing off from the articles being dried.

In testimony whereof, I have hereunto signed my name at Philadelphia, Pennsylvania, this 6th day of May, 1924.

WALTER W. SIBSON.
